(57) **CLAIM**

The ornamental design for an operating console for a printing machine, as shown and described.

DESCRIPTION

FIG. 1 is a top rear-right perspective view of an operating console for a printing machine showing my new design; and, FIG. 2 is a front-right perspective view thereof.

The left side of the operating console is a mirror image of the right side thereof.

1 Claim, 2 Drawing Sheets

FIG. 1
